UNITED STATES PATENT OFFICE.

DAVID GRANT, OF CHICAGO, ILLINOIS.

ARCH SUPPORT.

Application filed January 7, 1922. Serial No. 527,739.

To all whom it may concern:

Be it known that I, DAVID GRANT, a citizen of the United States, residing at Chicago, in the county of Cook and State 5 of Illinois, have invented new and useful Improvements in Arch Supports, of which the following is a specification.

This invention relates to arch supports, and an object of the invention is to provide 10 an arch support which is constructed of spring or resilient sheet metal embodying sufficient flexibility to permit it to flex under the weight of the user and with the movements of the foot of the user, and further 15 to construct the parts of the arch support in such manner that the movement and flexing of the parts thereof will be augmented, to provide an efficient arch support which will conform to the shape of the foot at 20 all times for properly supporting fallen or defective arches.

Other objects of the invention will appear in the following detailed description taken in connection with the accompanying 25 drawings wherein:

Fig. 1 is a top plan of the improved arch support.

Fig. 2 is a longitudinal section through the arch support.

Fig. 3 is a vertical section through the arch support taken on the line 3-3 of 30 Fig. 2.

Fig. 4 is a perspective view of one of the sections of the arch supporting plate structure.

Fig. 5 is a perspective view of the other section or plate of the arch supporting plate structure.

Fig. 6 is a detail perspective view of a 40 clip and bearing member embodied in the arch support.

Fig. 7 is a detail plan illustrating the manner of engagement between the bearing member and the ends of the flexible or 45 resilient arch supporting plate structure.

Referring more particularly to the drawings, the improved arch support comprises a resilient base plate 1 which is preferably 50 constructed of sheet metal, and is shaped to fit snugly within the shoe of the wearer. The body plate 1 is provided with transverse slots 2 and 3, at spaced points, and the por-

tions 4 of the plate directly outwardly of the slots are offset upwardly, above the upper flat surface of the plate to provide openings 55 through which the tongues 5 of the spring plate 6, and the tongues 7 of the spring plate 8 extend. Clips or plates 9 are riveted to the undersurfaces of the body plate 1 and they have upstanding bearing 60 projections 10 formed thereon which fit snugly beneath the undersurfaces of the upstruck portions 4. A reinforcing rivet 11 extends through the bearing projection 10, plate 9 and the upstruck portion 4, as 65 clearly shown in Fig. 2 of the drawings to securely attach the bearing portion 10 and plate 9 to the base plate 1. Each of the bearing members 10 is provided with a curved bearing edge 12 which is adapted to 70 engage in the curved recesses 13 formed in the tongues 5 and 7. The plates 6 and 8 which are constructed of resilient or spring sheet metal are bowed longitudinally as 75 clearly shown in the drawings, so as to fit snugly beneath the arch of the wearer's foot, and these plates are split at each end, as shown at 14 to respectively form the tongues 5 and 7 and also to provide bearing extensions 15 which engage in flatwise relation with each other and the base plate 1 at the ends of the slot 3. In the usual manner of assembling the arch support, the plate 8 is positioned adjacent the base plate 80 85 1 with the tongues 7 thereon inserted through the slots 2 and 3 after which the plate 6 is placed upon the plate 8 with the tongues 5 thereon extending through the slots 2 and 3 and in engagement with the bearing members 10 and also with certain 90 of the tongues 15 engaging the corresponding tongues 15 on the plate 8. The arcuate recesses 13 and the curved bearing edges 12 will permit a pivotal movement of the plates 6 and 8 relative to each other and 95 relative to the base plate 1, while the resiliency of the said plates will permit a flexing of the plates towards or from the base plate 1. The plate 6 has an upwardly and outwardly curving lateral extension 17 100 formed thereon which has an indentation 18 thereon and which is further curved and shaped to snugly fit against the inner side of the foot of the wearer adjacent the arch

of the foot. Greater flexibility is afforded the extension 17 than its inherent resiliency will permit, by means of the recesses or slots 19 which are cut in the plate 6 inwardly from each end of the extension 17.

The plate 8 which is also constructed of resilient sheet metal has a relatively small upwardly and outwardly curving side extension 20 formed thereon which is shaped 10 to snugly fit against the outer side of the foot adjacent the arch, and the edge of the plate opposite the edge upon which the extension 17 is formed is cut away as shown at 21 to increase the flexibility of the plate and decrease the weight of the arch support. Upon the weight of the wearer being applied to the resilient plates 6 and 8 during walking, the extensions 17 and 20 on these plates will flex inwardly upon the 20 downward flexing of the main body portions of these plates causing the extensions to move inwardly and maintain proper engagement with the foot of the wearer at all times. If it is so desired, it is to be understood that the plate 6 may be used independently of the plate 8 provided the conditions of the foot of the wearer do not need the plate 8.

The flexing of the plates 6 and 8 and their 30 extensions 17 and 20 caused by the walking of the wearer of the arch support will have a massaging effect upon the foot of the wearer which will cause healthy respiration of the foot, and warm or heat the foot, keeping the feet warm in cold weather.

From the foregoing description taken in connection with the accompanying drawings, it will be apparent that an arch support has been provided in which various adjustments 40 of the arch supporting plate structure may be obtained by variation of the plates 6 and 8, or by variation of the relative positions of these plates to accommodate the requirements in each individual or particular case, 45 and that an arch support has been provided in which a maximum flexibility and supporting features are provided, the said arch support being designed to yield in all directions and maintain snug fitting supporting engagement with the foot of the wearer, and 50 it is to be understood that the metal parts may be incased in a suitable cover as shown in my co-pending application filed September 24, 1921, Serial No. 502,939.

55 It is, of course, to be understood that the invention may be constructed in other manners and the parts associated in other relations and, therefore, I do not desire to be limited in any manner except as set forth 60 in the claims hereunto appended.

Having thus described my invention what I claim is:

1. In an arch support, a base plate, and a 65 yieldable arch supporting plate structure comprising a plurality of independent plates

separably connected to said base plate for yieldable and oscillatory movement relative to the base plate.

2. In an arch support, a base plate provided with spaced slots, and a resilient arch 70 supporting plate formed with tongues for insertion in the slots and a tongue pressing upon the top of the support, said arch supporting plate having a lateral extension formed integral therewith.

3. In an arch support, a base plate having spaced slots therein, clips secured to the base plate under said slots, bearing extensions on said clips having curved bearing surfaces, and a resilient arch supporting plate having tongues thereon for insertion through said slots, said tongues being provided with arcuate cut out portions for receiving and abutting said curved bearing portions.

4. In an arch support, a base plate, and a yieldable arch supporting plate structure comprising a pair of independent plates each 80 separably connected to the base plate for yieldable and oscillatory movement relative to the base plate, and extensions formed upon the side edges of said independent plates and curving outwardly and upwardly therefrom.

5. In an arch support, a base plate, and a 85 yieldable arch supporting plate structure comprising a pair of independent plates each separably connected to the base plate for yieldable and oscillatory movement relative to the base plate, and extensions formed 100 upon the side edges of said independent plates and curving outwardly and upwardly therefrom, one of said extensions being provided with an inwardly curved portion.

6. In an arch support, a base plate provided with spaced slots, a resilient arch supporting plate having splits extending inwardly from each end at spaced points and forming tongues for insertion through said slots to separably connect the resilient arch 105 supporting plate to the base plate, and an extension formed upon and curving upwardly and outwardly from one side edge of the arch supporting plate.

7. In an arch support, a base plate provided with spaced slots, an arch supporting plate structure formed of independent resilient plates each having tongues on their ends for engagement through said slots, clips attached to the undersurfaces of said base plate and forming pockets for receiving said tongues, and bearing surfaces on said clips, said tongues being provided with cut out portions forming bearing surfaces for engagement with the clip carried bearing 115 surface.

8. In an arch support, a base plate provided with spaced slots, an arch supporting plate structure formed of independent resilient plates each having tongues on their 120

ends for engagement through said slots, clips attached to the undersurfaces of said base plate and forming pockets for receiving said tongues, bearing surfaces on said 5 clips, said tongues being provided with cut out portions forming bearing surfaces for engagement with the clip carried bearing

surfaces, and relatively short tongues at each side of first named tongues for engagement with the upper surfaces of said base plate. 10

In testimony whereof I affix my signature.

DAVID GRANT.
